J. A. P. Richardson, Portland, Me.

Letter Patent No. 376, dated May 27, 1861

The structure referred to in these Letters Patent and making part, in some

To all Persons to whom these Presents shall come:

Be it known

that J. A. P. Richardson, of Portland in the County of Cumberland and State of Maine, have produced a new and original design for the front, side, and back plates of a Cooking Stove, and I do hereby declare, that the said new design is fully described and represented in the following specification and accompanying drawings, to which reference is herein after made.

The figures of the accompanying plates of drawings represent my new design. In plate 1. fig 1. is an elevation of the side plate and fig. 2. is a horizontal section of the same taken in the plane of the line A B. fig 1 - Fig. 3 is an elevation of the back plate. In plate 2. fig. 4 is an elevation of the upper front plate and fig 5 an elevation of the lower front plate.

Around each of the plates is the curved bead moulding a a a &c. Around the oven door of the side plate, the two smaller doors and the panel B, near the top of the plate, are the mouldings d. e. f. In the centre of the oven door is the piece of raised scroll work g. from which run four pieces of raised scroll work h. h. h. h. Four pieces of raised leaf work i. i. i. i. run from the corners towards the centre. Between these and near the moulding f, run the raised branches or vines k. k. &c.

The panel B is ornamented with the scroll work g with two branches h. h. The panel of the lower small door is ornamented in the centre by the scroll work g.

Wes. 376

while from each corner towards the centre run portions of the leaf work i. i. &c. On the outer edge of the panel are the pieces of branches or vines k. k. The upper small door is ornamented in a similar manner with the exception of the pieces of leaf work i. i.

The two doors of the upper front plate are ornamented with the mouldings d. e. f. scrolls g. g. and vines k. k. like the small fine chamber door in the side plate. On each side of these doors are panels formed by the mouldings l. m. In each of these panels is the leaf work i. i.

The lower front plate is ornamented with three pieces of leaf work i. i. i.

Having thus described my new design I shall state my claim as follows

What I claim as my production and desire to have secured to me by Letters Patent, is the design, consisting of the several mouldings, leaf work and scrolls, herein above described and represented in the drawings, for the front, side and back plates of a cooking stove.
